No. 853,612.

PATENTED MAY 14, 1907.

H. WILSON.
INDICATOR.
APPLICATION FILED OCT. 3, 1906.

UNITED STATES PATENT OFFICE.

HARRY WILSON, OF WASHINGTON, DISTRICT OF COLUMBIA, ASSIGNOR OF
ONE-HALF TO W. B. LINDSEY, OF WASHINGTON, DISTRICT OF COLUMBIA.

INDICATOR.

No. 853,612.

Specification of Letters Patent.

Patented May 14, 1907.

Application filed October 3, 1906. Serial No. 337,216.

To all whom it may concern:

Be it known that I, HARRY WILSON, a citizen of the United States of America, residing at Washington, in the District of Columbia, have invented certain new and useful Improvements in Indicators, of which the following is a specification, reference being had therein to the accompanying drawing.

This invention relates to certain new and useful improvements in indicators, and it relates more particularly to indicators adapted to be employed by time keepers and others for indicating or designating the time of arrival of employees.

The indicator broadly speaking is of that type adapted to be used in connection with a system wherein each employee is designated by a number, or equivalent designation, and the object of the present invention is to provide an indicator of this type in which movable indicator-elements or markers are employed, one for each employee, the said markers being normally visible, each indicator-element having a number or equivalent data on its outer or exposed face, and each indicator-element so mounted, that when moved by the employee, they will be shifted into hidden position, from which position they may only be removed by some one in charge of the apparatus.

Another object of the present invention is to provide a device of this character, which will be extremely simple in its construction, and cheap to manufacture, and one which will enable the determining of the exact time of arrival at work of any employee.

Still another object of the invention is to provide a device of this character in which danger of collusion or fraud among the employees, will be reduced to a minimum; furthermore, to provide a device in which any one or more of the indicating elements may be easily and quickly removed from the indicator board when desired for any purpose whatever.

The invention consists in the novel construction, combination and arrangement of parts to be hereinafter more fully described and then particularly pointed out in the claims, and in describing the invention in detail, reference will be had to the accompanying drawings forming a part of this application, and wherein like numerals of reference

will be employed to designate like parts throughout the several views, in which:—

Figure 1 is a front elevation of an indicator, or indicating board, constructed in accordance with my invention, and partly broken away, certain of the indicating elements being shown in their exposed position, and others thereof being shown in the hidden or concealed position. Fig. 2 is a transverse vertical sectional view taken on the line 2—2 of Fig. 1. Fig. 3 is a horizontal sectional view taken on the line 3—3 of Fig. 1. Fig. 4 is a detached detail perspective view of a part of one of the slotted strips which carry the movable indicating elements, one of said elements being shown at the limit of its movement in one direction, and another of the elements being shown at the limit of its movement in the opposite direction. Fig. 5 is a similar view showing the rear of a part of one of said strips; Fig. 6 is a detached detail perspective view showing the rear face of one of the indicating elements.

In construction the device embodies broadly a base-board 1, which, as will be understood, may be of any desired size, according to the number of markers or indicating elements which it is desired to accommodate. In the present illustration I have shown this base as provided with a pair of eyes 2, by means of which the same can be suitably suspended from a wall or the like, though of course this is not an essential feature of construction, as the indicator may be used in any manner found most desirable.

At the upper edge of the base 1, on the front face thereof, is a grooved or slotted guide-rail 3, and at the lower edge of the said base, also on the front face thereof, is a similar guide-rail 4. For convenience in manufacture these rails 3 and 4 are preferably grooved from end to end, and they receive the ends of a plurality of shiftable hiding strips 5, which may be of any desired material, though preferably an opaque material of some nature, by means of which when the indicating elements are shifted to position to lie back of the said strips, the said elements will be hidden from view. Each strip 5, is adapted to have a range of movement equal approximately to the width of the strip, and consequently to so limit the movement of each of these strips in the

grooved rails 3 and 4, the latter are provided with stop pins 6, 6.

Corresponding to the number of hiding strips 5, I provide carrying plates or strips 7, 5 disposed vertically on the front face of the base 1, between the guide-rails 3, 4, and spaced a short distance away from the front face of said base, which may be done by filler blocks or rests 8, as clearly seen in Fig. 2 of the drawings. These carrying plates or strips 7, are provided at equidistant intervals throughout their length with substantially segmental-shaped slots 9, terminating at one end in a slightly enlarged rounded opening 10, the purpose of which will hereinafter appear. In each of the said slots 9, there is adapted to be received the shank 11, of the indicating element or marker, in this instance in the form of a button or disk 12, the buttons or disks being numbered consecutively as shown. These buttons or disks are held in the slots 9, by the head 14, on the shank 11, which head is of a size which will be received within the opening 10, but is of a greater diameter than the width of the slot 9, so that the button or disk after being placed within the said slot 9, is held therein until positively removed. The shank 11, of said button or disk is, after being introduced into the slot 9, prevented from normally falling into the opening 10, and thereby permitting the button or disk to drop out, by means of a spring arm 15, attached at or adjacent one end, as by soldering, or in any other suitable manner to the carrying plates or strips 7. The other end of each of these arms is free, and the arms are so positioned on the rear face of the carrying plates or strips 7, as to lie directly back of the openings 10. It will be observed consequently, that when the buttons or disks constituting the indicating elements are in the exposed position as shown for certain of said indicating elements in Fig. 1 of the drawings, that the shank 11, rests on the arm 15, instead of falling into the opening 10. If at any time it is desired to remove any one or more of the indicating elements, the free end of the arm 15 is depressed toward the base 1, thus removing the support for the shank 11, of the button or disk, and allowing the shank of the latter to drop into opening 10, so that it may be removed from the slot. The arms 15, may be depressed by providing the carrying plates or strips 7 with a small opening 16, opposite each arm into which a pencil or any small diameter or pointed instrument may be placed to depress the said arms, or the free end of this arm may be extended slightly beyond the edge of the carrying plates or strips, as will be readily apparent.

Obviously locking means should be employed for securing the hiding strips 5, in their two respective positions, in order that

unauthorized persons may not shift these strips, and thus expose indicating elements intended, for the purpose of obtaining the desired record, to be hidden. Such lock however, may be of any type or pattern which will coöperate with the indicator board, and in the present illustration I have shown in dotted lines in Fig. 1 a longitudinally shiftable locking bar 17, provided with lugs 18, against which the hiding strips 5 engage. When this bar is shifted in one direction by a key inserted through key-opening 19, the hiding strips 5, will be locked in their one position, and in order to move the said strips 5, to their opposite position, the bar 17 is first moved, so as to permit the movement of the strips 5.

In operation, the device is placed in the office, or at any other point desired by the attendant whose duties it may be to keep a record of the workmen or employees. The numbered indicating elements are placed in their extreme or rest position at one end of the slots 9, exposed to view, as shown by the indicating elements numbered 1, 2 and 3, in Fig. 1 of the drawings. Assuming that the workman or employee who has been given No. 1, arrives at the office, he moves the said element or marker so as to cause it to ride in its slot 9, and disappear behind the hiding strip 5 assuming a rest position at the other end of said slot. When the time arrives for all of the employees or workmen to have reported, the attendant whose duties it is to keep a record of the time, can tell at a glance at the indicator, just what employees are absent, or have not reported, and may make note of the same as is desired. When it is again desired to use the indicator, the hiding strips 5, are simply shifted to the opposite position, thus again exposing all the indicating elements or markers, and the workmen or employees as they again report, simply move the markers so as to cause them to ride to the opposite ends of the slots 9. These markers or indicating elements are in practice so constructed that the shanks 11, ride very freely in the slots 9, and in order that an employee when moving his own marker or indicator-element may not accidentally cause the same to strike the indicator element above, and thus erroneously move the latter marker also to reported position, I preferably provide the carrying plates or strips 7, at two points above the slots 9, with lugs 20, which may be readily formed by simply cutting the plates or strips 7 and striking out the material so cut. The buttons or disks 12, being eccentrically mounted on their shanks 11, as clearly illustrated in Fig. 6 of the drawings, will, when they engage said lugs 20, turn or rotate as will be readily apparent in a manner which will not interfere with their free riding in the slots 9,

but they will be prevented from turning in such manner as to engage the marker or indicating element above.

An important feature of the invention, and one which makes the device particularly adapted for use in connection with the time-keeping of employees, is that of the markers or indicating elements being provided on the outer or exposed faces thereof with the numbers or equivalent data, and their being readily detachable from the carrying-member, as, when a marker is shifted to position where it is hidden by one of the strips 5, the number or other data belonging to that particular marker is also hidden, obviating danger of an erroneous reading of the board as might result were a part of the indicating data left exposed when the marker is shifted. The time-keeper or other attendant is thus enabled to "read" the board almost at a glance, and danger of an erroneous reading thereof is reduced to a minimum.

It will be observed that while the device is extremely simple and effective, for assisting the person or persons charged with the duties of determining the arrival of employees or workmen at the proper time, that it may be utilized for various other purposes as well, for instance, if a certain workman or employee is discharged, or laid off, the marker bearing his number can be readily removed in an instant from the board. Also, should an employee or workman be directed to perform a certain task which requires him to leave the factory, the system of the office may require that such workman or employee go to the indicating board and shift his marker thereon so as to show that he is absent, and the marker bearing his number remains hidden until he again reports. This however is illustrative simply of the various advantages which may be obtained by the utilization of the construction of indicator shown and described, the invention residing broadly in the utilization of the shiftable markers or indicating elements bearing or carrying the indicating numbers or equivalent marks or data, and the shiftable hiding strips therefor, and I consequently do not desire to limit myself to the particular construction shown, but claim broadly the right to make such alterations and changes therein as may come within the scope of the appended claims.

Having fully described my invention what I claim as new and desire to secure by Letters Patent is:

1. An indicator comprising an indicator-element carrying-member having a substantially segmental-shaped slot, an indicator-element comprising a disk having a shank engaging in the slot and shiftable freely therein, and means shiftable laterally in front of the carrying-member for hiding said indi-

cator-element when the latter is shifted to 65 extreme position at either end of the slot.

2. An indicator comprising a plurality of indicator-elements, supporting means for shiftably suspending said elements, and means to prevent engagement of one element 70 while being shifted with a stationary element, said means being located out of the normal shifting path of the elements.

3. An indicator comprising a plate having a plurality of substantially segmental-shaped 75 slots, and a corresponding number of indicator-elements having shanks adapted to enter said slots and movable freely therein from end to end of the slots, and lugs carried by the plate adjacent each slot to prevent engagement of one indicator-element while being shifted with a stationary indicator-element.

4. An indicator comprising a plurality of shiftable indicator-elements, means for suspending the elements, means located out of the normal shifting paths of the elements to prevent the engagement of one element while being shifted with a stationary element, and separate means for concealing the elements when shifted.

5. In an indicator, a base provided adjacent the upper and lower edges with grooved guide-rails, a plurality of carrying-plates carried by said base, a plurality of shiftable 95 markers or indicator-elements carried by each of said plates, and shiftable hiding strips, one for each carrying-plate and set of markers or indicator-elements.

6. In an indicator, a carrying-plate, a plurality of shiftable indicator-elements or markers carried by said plate, a shiftable hiding strip for said indicator-elements or markers, and means for locking said strip when shifted to either of its extreme positions.

7. An indicator comprising a plate having a plurality of substantially segmental-shaped slots arranged one above the other in the plate, a plurality of indicator elements, one for each slot, each indicator-element having 110 a shank adapted to move freely in the slots, means for retaining said shanks in the slots of said plate, and means carried by the plate adjacent each slot to prevent engagement of one indicator-element while being shifted 115 from one end of the slot to the other with a stationary element.

8. In an indicator, a plate provided with a plurality of slots terminating at one end in an enlarged opening, and a plurality of indicator-elements, one for each slot, each indicator-element comprising a disk having a shank received in the slot, a head on the shank for maintaining the same in the slot, and spring arms carried on the rear face of the plate and 125 normally closing said enlarged openings to prevent the shanks of said indicator-elements dropping into the same.

9. In an indicator, a plate provided with a plurality of substantially segmental-shaped slots, a plurality of consecutively-numbered indicator-elements, one for each slot, and shiftable to two rest positions in the respective ends of said slots, and means carried by the plate and located out of the normal shifting path of the elements to prevent the engagement of one indicator-element while 10 being shifted in its slot with an adjacent stationary element.

10. In an indicator, a manually-operated indicator-element, a shifting-path for said element, a hiding-strip shiftable over said path, said strip when in position at either of 15 its extremes of movement concealing a portion of said path, said strip being of sufficient width to conceal said element, whereby said

element may be moved from an exposed to an unexposed position, the latter position becoming the exposed position when the strip is shifted. 20

11. In an indicator, an indicator element shiftable between two positions, and a shiftable hiding-strip for rendering said element 25 unexposed, the movement of said strip from one extreme of its position to the other rendering the unexposed element to an exposed position.

In testimony whereof I affix my signature 30 in the presence of two witnesses:

HARRY WILSON.
